UNITED STATES PATENT OFFICE.

WILLIAM S. HAMM, OF CHICAGO, ILLINOIS.

LANTERN.

SPECIFICATION forming part of Letters Patent No. 529,787, dated November 27, 1894.

Application filed April 15, 1893. Serial No. 470,451. (No model.)

To all whom it may concern:

Be it known that I, WILLIAM S. HAMM, a citizen of the United States, residing in Chicago, in the county of Cook and State of Illinois, have invented certain new and useful Improvements in Lanterns, of which the following is a specification.

My invention is intended more particularly for railway lanterns but is applicable to others.

The object of my invention is to raise and lower the wick without removing the lamp from its place in the lantern. To this end I apply to the lamp a ring concentric with the burner and adapted to engage the wick-wheel by which the wick is ordinarily raised and lowered. The ring and wick-wheel may be toothed, or otherwise adapted to engage, the essential being that the rotation of the wick-wheel shall be determined by the rotation of said ring. This ring I connect with a second ring conveniently located on the lamp. The connection is made preferably by rods which embrace the lamp and hold the two rings in place. I also use a thumb-wheel attached either to the lamp or to the body of the lantern and adapted directly or indirectly to act upon the second ring above mentioned, rotate it, and through it the first ring thereby acting upon the wick.

In the drawings: Figure 1 is a partial vertical section, and Fig. 2 is a plan diagram showing the upper part of the lamp and the devices for acting on the wick.

1 is the body of the lantern while I have omitted the usual cage and cap of the lantern for simplicity's sake.

2 is the globe.

3 is the lamp.

4 is the burner.

5 is the usual wick-wheel, and 6 the stem by which, ordinarily, the wick is raised and lowered.

7 is a ring preferably concentric with the burner and adapted to engage the wick-wheel 5 either by means of teeth or otherwise so that it will rotate the latter.

8 are rods, preferably of spring metal, supporting the ring 7, extending down the side of the lamp and engaging a groove 9 in the lamp so as to maintain the ring in place.

10 is a ring surrounding the body of the lamp and connected to the lower ends of the rods 8.

11 is a thumb-wheel outside the lantern-body connected by a stem with the toothed-wheel 12 inside the body. The wheel 12 engages with the ring 10 and turns the latter when the thumb-wheel 11 is turned by the operator. Thus the wick is raised and lowered without removing the lamp from its place in the lantern. The wheel 12 is so combined with the ring 10 as that the latter will leave it when the lamp is taken out of the lantern and will engage it again when the lamp is put back.

The rods 8 may be made to embrace the lamp with sufficient friction to prevent any accidental disturbance of the wick from jarring or swinging of the lantern or other cause.

I hereby disclaim, as a part of my present invention, the construction set forth and claimed in my application Serial No. 470,452, filed of even date herewith, in which a horizontal hand ring outside the lantern is connected with an interior horizontal toothed ring engaging the gear of the wick raising stem.

I claim—

The combination, with a lantern and lamp, of a lower gear ring connected to the lamp, an upper gear ring adapted to engage a toothed wick wheel, rods connecting the two gear rings, and a thumb wheel outside the lantern and provided with a stem and a toothed wheel inside the body of the lantern, said wheel engaging the lower gear ring in such manner as to allow detachment therefrom when the lamp is taken out of the lantern, substantially as set forth.

WILLIAM S. HAMM.
